INVENTOR

BY Victor J. Evans

ATTORNEY

UNITED STATES PATENT OFFICE.

CHARLES B. COALWELL, OF PINE ISLAND, MINNESOTA, ASSIGNOR OF ONE-HALF TO CORTEZ A. MELLINGER, OF PINE ISLAND, MINNESOTA.

DAMPER.

Application filed February 15, 1921. Serial No. 445,202.

To all whom it may concern:

Be it known that I, CHARLES B. COALWELL, a citizen of the United States, residing at Pine Island, in the county of Goodhue and 5 State of Minnesota, have invented new and useful Improvements in Dampers, of which the following is a specification.

This invention relates to an automatic damper for stoves, furnaces and the like, the 10 general object of the invention being to provide a damper which will be closed when the draft in the chimney is increased beyond a certain point with means for changing this point.

15 Another object of the invention is to provide adjustable weighted means for controlling the movement of the damper.

This invention also consists in certain other features of construction and in the 20 combination and arrangement of the several parts, to be hereinafter fully described, illustrated in the accompanying drawings and specifically pointed out in the appended claims.

25 In describing the invention in detail, reference will be had to the accompanying drawings wherein like characters denote like or corresponding parts throughout the several views, and in which:—

30 Figure 1 is a fragmentary view of a stove-pipe supplied with my invention, parts being shown in section.

Figure 2 is a detail sectional view taken on line 2—2 of Figure 1.

35 In these views 1 indicates a part of a stove pipe which connects the stove or furnace with the chimney. This pipe has a hole 2 therein through which passes the rod 3 which is secured to the damper plate 5.

40 That part of the rod which passes through the opening is curved so as to provide a fulcrum for permitting the swinging movement of the damper plate without the rod sliding through the opening. The exterior

45 part of the rod is of substantially U-shape as shown at 6 and the limb of the U which is connected with the damper plate is bent to provide a series of depressions 7 for receiving the ring 8 of the weight 9. Thus 50 the weight may be adjusted along the lower limb of the U-shaped part of the rod to

counter balance the weight of the damper plate 5. I prefer to make the damper plate with upwardly curving portions 5', as shown.

When the draft in the chimney increases 55 beyond a certain point, either due to the velocity of the wind or the amount of heat produced by the fire in the stove or furnace, the damper will be moved upwardly by the pressure and suction created by the 60 draft and thus the fire will be checked in the stove. By adjusting the weight on the rod the point of closing of the damper can be regulated as desired. By my invention an even draft is secured in the stove which 65 acts to conserve fuel.

By making the damper plate of the shape shown the current of air will hold said plate in a horizontal position when the draft is strong and the plate is prevented from 70 striking either side of the pipe as it would do if the plate was flat.

It is thought from the foregoing description that the advantages and novel features of my invention will be readily apparent. 75

I desire it to be understood that I may make changes in the construction and in the combination and arrangement of the several parts, provided that such changes fall within the scope of the appended claims. 80

What I claim is:—

1. In combination with a chimney pipe, a damper plate therein, a rod secured to said plate and passing through a hole formed in said pipe, the part of the rod which passes 85 through said opening being curved to provide a fulcrum for permitting the swinging movement of the damper plate without the rod sliding through said opening and the exterior part of said rod being of U- 90 shape and having the limb of the U connected with said damper plate and bent to provide a series of depressions, a ring adapted to engage said depressions and a weight carried by said ring for counter balancing 95 the weight of the damper plate.

2. A device of the class described comprising a stove pipe adapted to connect the latter with a chimney, said pipe having a hole formed therein and a rod passing 100 through said hole, a damper plate secured to said rod, the part of the rod which passes

through said hole is curved to provide a fulcrum for permitting the swinging movement of the damper plate without the rod sliding through the opening, said rod having its exterior part of U-shaped formation and the limb of the U being connected with a damper plate and bent to provide a series

of depressions, a ring carried by the limb of the U and a weight secured to one end of said ring, said damper plate having upwardly curved portions. 10

In testimony whereof I affix my signature.

CHARLES B. COALWELL.
